ELECTRIC DIRECTION INDICATOR

Henry J. Elliott, Hopewell, Va.

Application June 1, 1939, Serial No. 276,876

3 Claims. (Cl. 177—329)

This invention relates to an electric direction indicator and has for an object to provide a simplified warning signal for motor vehicles adapted to indicate to other drivers and to pedestrians the intentions of a driver to turn to the right or left, to stop or to back.

5

A further object is to provide improved means for controlling the rotation of the legend displaying drum, the same including essentially a 10 pair of solenoids having a common endwise movable core geared to the drum, and an additional solenoid having a core disposed to engage the first named core and limit endwise movement thereof for controlling the drum to display a 15 "left" or "back" signal.

A further object is to provide an improved manually operable switch electrically connected to the solenoids and to a pilot bulb and a bulb for illuminating the legends, the switch when in 20 one position serving to connect the source of current to a brake pedal operated switch so that the signal "back" and "stop" may be also controlled by the brake pedal.

A further object is to provide a device of this 25 character which will be formed of a few strong, simple and durable parts, which will be inexpensive to manufacture, and which will not easily get out of order.

With the above and other objects in view the 30 invention consists of certain novel details of construction and combinations of parts hereinafter fully described and claimed, it being understood that various modifications may be resorted to within the scope of the appended claims without departing from the spirit or sacrificing any 35 of the advantages of the invention.

In the accompanying drawings forming part 40 of this specification:

Figure 1 is a perspective view of the signal lamp constructed in accordance with the invention.

Figure 2 is a cross sectional view of the lamp taken on the line 2—2 of Figure 3.

Figure 3 is a longitudinal sectional view of the 45 signal lamp.

Figure 4 is a perspective view of the drum and displaying the signal legend as well as the initials of the vehicle owner.

Figure 5 is a plan view of the hollow armature 50 or core which is common to two of the solenoids and showing the core of a third solenoid engaged therewith.

Figure 6 is a plan view of the manually controlled switch.

Figure 7 is a cross sectional view of the switch 55 taken on the line 7—7 of Figure 6.

Figure 8 is a cross sectional view of the switch taken on the line 8—8 of Figure 7.

Figure 9 is a diagrammatic view of the electrical connections of the correction indicated.

Referring now to the drawings in which like characters of reference designate similar parts in the various views, 10 designates a cylindrical lamp casing having the open ends closed by transparent panes 11. A sight opening 12 is formed longitudinally of the casing and is provided with a transparent pane 13 through which the legends of the signal drum 14 are exposed. Diametrically opposite the sight opening, the casing is provided with a bracket 15 through the medium of 10 which the casing may be secured to the motor vehicle, as for example to the door of the baggage compartment as shown in Figure 1.

The signal drum 14 is in the form of a cylinder having substantially one-half thereof cut 15 away longitudinally to near the ends. A transparency 16 closes the cut away portion and bears the legends "Right," and "Left," then the initials of the owner of the vehicle, then the legends "Back" and "Stop," arranged in a vertical row 20 as shown in Figure 4. The drum is provided at the ends with radially extending brackets 17, best shown in Figures 3 and 4, these brackets being substantially a radius of the drum in length. The brackets extend from the drum in the same 25 general direction and are provided with openings 18 at the inner ends to receive the reduced ends of a shaft 19.

The shaft 19 extends axially in the lamp casing 10 and is rotatably supported at the ends 30 in bearings 20 disposed on the upper ends of a pair of standards 21 which rise from an inverted U-shaped base bar 22. The bar 22 extends longitudinally through the drum, parallel to the shaft 19, and is provided with out-turned ends 35 23 which are fixed to the casing 10 as shown at 24. The openings 18 in the brackets 17 are each provided with a straight wall 25, best shown in Figure 4, to receive a flat portion 26 on the respective end of the shaft 19 to mount the drum 40 for rotation with the shaft as a unit. Nuts 27 are threaded on to the ends of the shaft and detachably secure the drum to the shaft. The shaft is provided with a pinion 28, best shown in Figures 2 and 3, for rotating the shaft as will 45 now be described.

Two solenoids 29 and 30 are mounted in axial alignment transversely of the drum through the medium of respective strap brackets 31 and 32 which are secured to the base bar 22 as shown at 50 33 and 34. The axis of the solenoids extends at a right angle to the shaft 19. A hollow armature 35, common to both solenoids, is mounted for endwise movement in the solenoids and is limited in endwise movement by caps 36 and 37 which 55 close the outer ends of the solenoids. Rack teeth 38 are formed on the upper surface of the armature and mesh with the teeth of the pinion 28.

When the armature is moved endwise in either direction, the drum 14 is consequently rotated 60

axially by the pinion. For yieldably holding the armature in neutral position, a pin 39 is disposed longitudinally in the bore of the armature and is secured stationary through the medium of nuts 40 threaded onto the ends of the pin and engaging the caps 36 and 37. The pin is provided with a central projection 41 which is disposed within an annular collar 42 formed at the center of the bore of the armature. A pair of helical springs 43 and 44 are sleeved on the pin, the outer ends of the springs bearing against the caps 36 and 37 and the inner ends of the springs bearing against respective washers 45 and 46 disposed loosely on opposite sides of the projection 41.

By referring to Figure 2 it will be seen that when the solenoid 29 on the right of the figure is energized, the armature 35 will be drawn thereto with resultant rotation of the pinion 28 and drum 14 counter-clockwise to display the legends "back" or "stop" selectively through the sight opening 12. During this movement of the armature the annular collar 41 moves the washer 45 outwardly and compresses the spring 43. As soon as the solenoid is deenergized the spring expands and returns the armature and drum to neutral position, in which position of the drum the initials of the owner, for example, "J F D" are displayed through the sight opening.

When the solenoid 30 on the left of Figure 2 is energized, the armature 35 will be drawn thereto with resultant rotation of the pinion 28 and drum 14 clockwise to display either the legend "right" or the legend "left" selectively through the sight opening 12. The annular collar 42 impinges against the washer 46 to compress the spring 44 when the solenoid is energized and when the solenoid becomes deenergized the spring expands and returns the armature 35 to neutral position.

The legend "right" or "stop" will be displayed when the drum is permitted to advance to its limit of stroke in either direction. For limiting movement of the drum to one-half stroke in either direction, and thus selecting the legend "left" or "back" to be displayed, a third solenoid 47 is secured to the base bar 22 through the medium of bracket arms 48 best shown in Figure 3. The solenoid is provided with an armature 49 having a projection 50 at one end adapted to enter a recess 51 in the hollow armature 35, as best shown in Figures 3 and 5, and limit rotation of the drum to one-half stroke when the solenoid 47 is energized.

A helical spring 52 is sleeved on the armature 49 and at one end bears against a flange 53 secured to the end of the armature and at the other end bears against a flange 54 projecting from a guide tube 55 disposed in the bore of the solenoid 47. The tube is closed at the outer end through the medium of a cap 56 which forms a stop to limit withdrawal of the armature, under urge of the spring 52, from the recess 51 when the solenoid 47 is deenergized.

For controlling the solenoids a selective switch is provided, as shown in Figures 6, 7 and 8. The switch may be located within convenient reach of the driver and comprises a casing 57 having a switch base 58 of insulating material disposed longitudinally therein. The top wall 59 of the casing is provided with a cruciform slot 60, the arms of which are designated by respective characters, "L" for "left," "R" for "right," "B" for "back," and "S" for "stop." A switch arm 61

projects through the slot and is equipped outside of the casing with a knob 62.

The switch arm is provided inside of the casing with a ball 63 formed of metal and which is loosely confined in a metal socket 64 which is secured to the insulating base 58 by screws 65. Diametrically opposite the arm 61 the ball is formed with an integral arm 66 through the medium of which current from the source of supply 67, such as a battery, is brought through a wire 68, to any one of four stationary switch contacts 69, designated as shown in Figure 8, as, "R" for "right," "L" for "left," "B" for "back" and "S" for "stop," arranged a quadrant distance apart in an insulated flange 10 which projects downwardly from the insulating base 58 concentric with the axis thereof.

Each switch contact 69 is formed of four resilient metal tongues embedded at the outer ends in the flange 10, the two inner tongues forming switch contacts to be bridged by the arm 66, and the other two forming stops to limit expanding movement of the inner contacts, one of the other two also forming a switch contact to be energized when the inner two switch contacts are spread apart by the arm 66. The electrical connections are such that when the selective switch is operated, one of the aligned solenoids is energized to give a respective signal, the other solenoid of the aligned solenoids is energized to give another selective signal. Either of the two remaining signals is given by energizing one of the aligned solenoids and by simultaneously energizing the third solenoid as will be seen by reference to Figure 9.

Right turn

The stationary switch contact designated "R," corresponding to the "right" legend, is connected by a wire 71 to the solenoid 30 of the aligned solenoids for actuating the signal drum to display the "right" legend indicative of a right turn.

Stop signal

The stationary switch contact designated "S" corresponding to the "stop" legend, is connected by a wire 72 to the other aligned solenoid 29 for actuating the signal drum to display the "stop" legend indicative of the driver's intention to stop.

Left turn

One of the outer tongues of the stationary switch contact designated "L," corresponding to the "left" legend, is connected by a wire 73 to the third solenoid 47. One of the inner tongues of this switch contact is connected by a wire 74 to the solenoid 30 of the aligned solenoids. Thus when the selective switch is operated to engage the "left" turn stationary switch contact the solenoid 30 of the aligned solenoids will be energized and, at the same time, the third solenoid 47 will be energized to limit the stroke of the signal drum to one-half so that it will display the legend "left" at the sight opening 12.

Back signal

One of the outer tongues of the switch contact designated "B," corresponding to a "back" legend, is connected by a wire 75 to the other solenoid 29 of the aligned solenoids while one of the inner tongues of this switch contact is connected by a wire 76 to the third solenoid 47. Consequently when the selective switch is operated to engage the stationary switch contact corresponding to a "back" signal the solenoid 29 of the aligned solenoids will be energized and simultaneously the

- third solenoid 47 will be energized to limit the stroke of the signal drum to one-half stroke so that the legend "back" will be displayed at the sight opening.
- 5 The remaining inner tongue of each stationary switch contact is connected to a common circuit wire 77 which is in series with a pilot bulb 78 in the selective switch casing and a legend illuminating bulb 79 on the bar 22.
- 10 It is desirable that the brake pedal be utilized also to operate the "stop" signal. For this purpose a brake pedal operated switch is provided, comprising a bridging contact 80 which is connected to the brake pedal 81 by a link 82 and is adapted to bridge three stationary switch contacts 83, 84 and 85. A wire 86 is connected to the contact 83 and is connected to the solenoid 29. A wire 87 is connected to the contact 84 and is connected to the common circuit wire 87 which is in series with the bulbs 78 and 79. A wire 88 is connected to the contact 85 and is connected to a switch contact 90 to bring power from the power wire 68 through the switch arm 66, best shown in Figure 6.
- 25 When the brake pedal is depressed the bulbs will be energized and, at the same time, the solenoid 29 will be energized through its full stroke to actuate the signal drum for displaying the signal "stop" at the sight opening.
- 30 As best shown in Figure 7 the contact 90 comprises a dished metal plate which is supported upon an insulating base 91 carried by brackets 92 disposed on the bottom of the insulating flange 70. The power wire 88 to the brake pedal switch 35 is connected to a metal pin 93 which slidably extends through the insulating base 91 and which is fixed to the plate 90. Sleeved upon the pin is a helical spring 94 which holds the plate 90 in good electrical contact with the arm 66 of the selective switch when the selective switch is 40 in neutral position to close the power circuit at this point to the brake pedal operated switch.
- 45 Since the operation of the device has been described, as the description of the parts progressed, it is thought that the invention will be fully understood without further explanation.
- What is claimed is:
1. In an electrical direction indicator, a casing having a sight opening, a rotatable drum in the casing adapted to display signal legends "right," "left," "back" and "stop" through said opening, a shaft connected to the drum for rotating the drum, a pinion fixed to the shaft, a pair of aligned solenoids disposed at opposite sides of the 50 shaft, an armature movable endwise through both solenoids and having rack teeth engaging the pinion for rotating the drum when either of the solenoids is energized, a rod extending axially through the armature, supports carried by the solenoids to which the rod is fixed at the ends, a stop projection on the center of the rod, washers loose on the rod on opposite sides of the stop projection, a collar on the inner wall of the armature engaged between said collars, helical springs 55 sleeved on the rod between the supports and the washers normally holding the drum in non-signaling position, there being a recess in the side of the armature, and a third solenoid having an armature adapted to engage in said recess and limit stroke of the toothed armature to one-half stroke, respective circuits corresponding to the signal legends connected to the first named solenoids, a source of electricity, circuits connected to the source of electricity corresponding to said signal legends 60 connected to said third solenoid and connected in parallel with respective ones of the first named circuits, and circuit closers for said circuits.
- 65
2. In an electrical direction indicator, a casing having a sight opening, a rotatable drum in the casing adapted to display signal legends "right," "left," "back" and "stop" through said opening, a shaft connected to the drum for rotating the drum, a pinion fixed to the shaft, a pair of aligned solenoids disposed at opposite sides of the shaft, an armature movable endwise through both solenoids and having rack teeth engaging the pinion for rotating the drum when either of the solenoids is energized, means for yieldably holding the drum in non-signaling position, there being a recess in the side of the armature, and a third solenoid having an armature adapted to engage in said recess and limit stroke of the toothed armature to one-half stroke, respective circuits corresponding to the signal legends connected to the first named solenoids, a source of electricity, circuits connected to the source of electricity corresponding to said signal legends two of the circuits being connected to one of the aligned solenoids and two of the circuits being connected to the other of the aligned solenoids, circuits corresponding to two of the signal legends connected to said third solenoid and connected in parallel with respective ones of the first named circuits, and circuit closers for said circuits.
- 70

said signal legends, two of the circuits being connected to one of the aligned solenoids and two of the circuits being connected to the other of the aligned solenoids, circuits corresponding to two of the signal legends connected to said third solenoid and connected in parallel with respective ones of the first-named circuits, and circuit closers for said circuits.

2. In an electrical direction indicator, a casing having a sight opening, a rotatable drum in the casing adapted to display signal legends "right," "left," "back" and "stop" through said opening, a shaft extending axially through the drum, a pair of brackets extending from the shaft in the same direction and secured to the ends of the shaft and to the ends of the drum, standards having bearings rotatably receiving the shaft, a pinion fixed to the shaft, a pair of solenoids arranged at opposite sides of the shaft, a hollow armature common to both solenoids provided with rack teeth engaging the pinion, a stationary rod extending axially in the hollow armature, supports for the rod, sliding washers on the rod, a stop projection at the center of the rod between the washers, an annular collar 25 in the bore of the armature disposed between the washers, helical springs sleeved on the rod between the supports and the washers for normally holding the drum in non-signaling position, the armature being provided in a side thereof 30 and centrally between its ends with a recess, and a third solenoid arranged perpendicular to the hollow armature and having a spring pressed armature adapted to engage in said slot when the third solenoid is energized, respective circuits 35 corresponding to the signal legends connected to the first-named solenoids, a source of electricity, circuits connected to the source of electricity corresponding to said signal legends, two of the circuits being connected to one of the aligned solenoids and two of the circuits being connected to the other of the aligned solenoids, circuits corresponding to two of the signal legends connected to said third solenoid and connected in parallel with respective ones of the first-named circuits, and circuit closers for said circuits.

3. In an electrical direction indicator, a casing having a sight opening, a rotatable drum in the casing adapted to display signal legends "right," "left," "back" and "stop" through said opening, a shaft connected to the drum for rotating the drum, a pinion fixed to the shaft, a pair of aligned solenoids disposed at opposite sides of the shaft, an armature movable endwise through both solenoids and having rack teeth engaging the pinion for rotating the drum when either of the solenoids is energized, means for yieldably holding the drum in non-signaling position, there being a recess in the side of the armature, and a third solenoid having an armature adapted to engage in said recess and limit stroke of the toothed armature to one-half stroke, respective circuits corresponding to the signal legends connected to the first named solenoids, a source of electricity, circuits connected to the source of electricity corresponding to said signal legends two of the circuits being connected to one of the aligned solenoids and two of the circuits being connected to the other of the aligned solenoids, circuits corresponding to two of the signal legends connected to said third solenoid and connected in parallel with respective ones of the first named circuits, and circuit closers for said circuits.

HENRY J. ELLIOTT.
